UNITED STATES PATENT OFFICE

167,247

PAPER TOWEL AND WAX PAPER DISPENSER

Louis H. Barnett and Harris Brin, Fort Worth,
Tex., assignors to Loma Plastics, Inc., Fort
Worth, Tex., a corporation of Texas

Application February 27, 1952, Serial No. 18,688

Term of patent 14 years

(Cl. D4—3)

To all whom it may concern:

Be it known that we, Louis H. Barnett and Harris Brin, both citizens of the United States, and both residing at Fort Worth, county of Tarrant, and the State of Texas, have invented a new, original, and ornamental Design for Paper Towel and Wax Paper Dispenser, of which the following is a specification, reference being had to the accompanying drawing, forming part thereof.

We claim:

The ornamental design for a paper towel and wax paper dispenser, substantially as shown.

LOUIS H. BARNETT.
HARRIS BRIN.
